(57) **CLAIM**

The ornamental design for a bracket for device, as shown and described.

DESCRIPTION

FIG. 1 is a front perspective view of a bracket for device, showing our new design;

FIG. 2 is a front view thereof;

FIG. 3 is a rear view thereof;

FIG. 4 is a side view thereof;

FIG. 5 is a left side view thereof;

FIG. 6 is a right side view thereof;

FIG. 7 is a bottom view thereof;

FIG. 8 is a rear perspective view thereof;

FIG. 9 is a rear view thereof as shown in an environment of use; and,

FIG. 10 is another rear view thereof as shown in an environment of use.

The broken lines shown in FIGS. 1–8 illustrate portions of the bracket for device that form no part of the claimed design. The broken lines illustrating the monitor and stand in FIGS. 9–10 are environment, while the remaining broken lines in FIGS. 9 and 10 illustrate portions of the bracket for device that form no part of the claimed design.

1 Claim, 10 Drawing Sheets
